The ornamental design for an odor neutralizer for an air conditioner, as shown and described.

DESCRIPTION

FIG. 1 is a perspective view of an odor neutralizer for an air conditioner, showing my new design;

FIG. 2 is top plan view thereof;

FIG. 3 is a front elevational view thereof;

FIG. 4 is a rear elevational view thereof; and,

FIG. 5 is right side elevational view thereof.

The bottom plan view is a mirror image of the top plan view, and the left side elevational view is a mirror image of the right side elevational view.
